ROLLER LATCH

John Warren Aurandt, Charlotte, N. C.

Application December 4, 1945, Serial No. 632,754

4 Claims. (Cl. 292—73)

1

The object of my invention is to provide a novel roller latch to operate quietly and effectively and will eliminate the scraping of the latch which occurs with the bevel latches now in general use. I attain these and other objects of my invention by the mechanism illustrated in the accompanying drawings, in which:

Figure 1 is a top plan view of a latch, a portion of the latch socket being shown in section;

Fig. 2 is an end view of the latch;

Fig. 3 is a plan view of the socket member;

Fig. 4 is a side elevation of the latch;

Fig. 5 is a side elevation of a modified form of the latch with the modified latch socket shown in vertical section;

Fig. 6 is a perspective view of a modified form of the invention illustrating a roller latch applied to a door;

Fig. 7 is a top plan view of the roller latch with the latch socket shown in section;

Fig. 8 is a side elevation of the roller latch shown in Fig. 7;

Fig. 9 is a face view of the socket member of the roller latch; and

Fig. 10 is a front elevation of the latch member and adjacent parts of the door.

Like numerals indicate like parts in each of the several views.

Referring to the accompanying drawings, I provide a rubber ball 1, rotatably mounted on an axle 2, which is mounted in a bracket 3, which is integral with a base 4, that is fastened to the door 6, by screws 5. I provide a latch frame or base 7, having an integral socket 8 adapted to receive the rubber ball 1. The sides 9 of the socket element 8, are beveled as shown in Fig. 1 and the base 7 is fastened to the door frame by screws 10.

Referring to Fig. 5, there is illustrated a modified latch socket 12 having an integral base 11, which is fastened to the door frame. The socket member 12 has a curved or beveled lip 13 for the rubber ball to roll over. Base 11 is fastened to the door frame by screws 14.

In use the resilient ball latch rides over the beveled side 9 and seats in the latch socket 8, thus holding the door tightly closed. In Fig. 5 a similar operation occurs, ball 1 riding over the curved lip 13 and into the latch socket 12.

Referring to the modified form of the invention shown in Figs. 6-10, I provide a roller latch 15 mounted on the axle 16, which in turn is mounted in brackets 17 extending from the bracket base 18. Bracket base 18 has a stem 19, on which is mounted a spring 20, tending to press

the roller latch outwardly. Bracket base 18 is slidably mounted in a guide or socket 22 provided in a housing 21 mounted in the edge of the door. Roller latch 15 normally seats in the socket 24 of the door latch member 23.

In operation the roller 15, carried by bracket 17, and base 18, is resiliently pressed outwardly by the spring 20 and will ride into a seat in the roller socket 24 to securely hold the door in latched position.

What I claim is:

1. A roller latch comprising a rigidly mounted bracket having laterally spaced outwardly extending arms, a roller element formed of elastic material and rotatably mounted between said arms, said roller being tapered outwardly to provide a relatively narrow resiliently compressible peripheral portion, and a latch socket having a recess shaped complementary to the peripheral portion of said roller, and a beveled portion extending from the edge of said recess and adapted to progressively compress said peripheral portion as the roller approaches said socket.

2. A roller latch comprising a rigid bracket having laterally spaced outwardly extending arms, a spherical roller formed of elastic rubbery material and rotatably mounted on a rigid axle extending diametrically therethrough, said axle being mounted between the ends of said arms, a latch socket operatively mounted for engaging said roller latch and provided with a complementary segmental spherical shaped recess for engaging said spherical roller and a beveled portion extending from the edge of said recess for progressively compressing the peripheral portion of said roller as the roller approaches said socket.

3. A roller latch comprising a rigidly mounted bracket having laterally spaced outwardly extending arms, a roller element formed of elastic material and rotatably mounted between said arms, said roller being tapered outwardly to provide a relatively narrow resiliently compressible peripheral portion and a latch socket comprising a marginal flange for securing the same to a support, a raised central portion joined to said flange by inclined walls and a recess in said central portion complementary to the peripheral portion of said roller, one of said inclined walls serving to engage and progressively compress said peripheral portion as said roller approaches said socket.

4. A roller latch comprising a rigidly mounted bracket having laterally spaced outwardly ex-

tending arms, a roller element formed of elastic material and rotatably mounted between said arms, said roller being tapered outwardly to provide a relatively narrow resiliently compressible peripheral portion and a latch socket comprising a plate for securing the same to a support, a portion attached to said plate and extending at substantially right angles thereto, a recess in said portion complementary to the peripheral portion of said roller, the edge of said portion being curved to provide a lip serving to engage and progressively compress said peripheral portion as said roller approaches said socket.

JOHN WARREN AURANDT.
